United States Patent Office

Des. 232,884
Patented Sept. 24, 1974

232,884

SEAT

Howard I. Niederman, 3757 S. Ashland Ave.,
Chicago, Ill. 60609

Filed Aug. 23, 1972, Ser. No. 283,187

Term of patent 3½ years

Int. Cl. D6—01

U.S. Cl. D6—63

FIG. 1

FIG. 2

FIG-3FIG-4FIG. 1 is a front perspective view of a seat embodying my design in the form of a sofa;

FIG. 2 is a side perspective view of the seat in the form of a loveseat;

FIG. 3 is a side perspective view of the seat in the form of a chair; and

FIG. 4 is a view in side elevation of the seat, the side not shown being a mirror image of the side shown.

I claim:

The ornamental design for a seat, as shown.
